UNITED STATES PATENT OFFICE

2,291,225

WIRE-STITCHING MACHINE

George H. Harred, East Greenwich, R. I., assignor
to Boston Wire Stitcher Company, Portland,
Maine, a corporation of Maine

Application January 10, 1941, Serial No. 373,947

22 Claims. (Cl. 1—11)

This application is a continuation in part of my copending application for Wire-stitching machine, Serial No. 329,912, filed April 16, 1940, and issued into United States Letters Patent No. 2,266,550, dated December 16, 1941.

In my prior application, referred to above, the wire-stitching machine illustrated and described is adapted for stitching the seams of boxes, cartons or the like and comprises a tie-stitch mechanism for applying the first and last two stitches of a series closely adjacent each other to strengthen the seam at its ends.

One of the objects of the present invention is to provide a simple form of tie-stitch mechanism which is operative on the work-feeding means to cause the latter to advance the work a reduced increment of movement between certain stitches.

Another object is to provide a tie-stitch mechanism of the type indicated which is maintained operative during the application of the last stitch of one series and the first two stitches of the next series.

Another object of the invention is to provide a tie-stitch mechanism of the type indicated which is set for operation by a cam on the control shaft and released by a trip actuated from the control shaft.

Another object is to provide a tie-stitch mechanism of the type indicated which is adjustable to adapt it to operate at the beginning and end of a row of any predetermined number of stitches.

Another object is to provide a tie-stitch mechanism of the type indicated which is of simple and compact construction and adapted for use over long periods of time without repair or replacement of parts.

Further objects of the invention are set forth in the following specification which describes a preferred form of construction of the tie-stitch mechanism, by way of example, as illustrated by the accompanying drawings. In the drawings:

Fig. 1 is a side elevational view of a wire-stitching machine incorporating the novel features of the present invention;

Fig. 2 is an enlarged side elevational view of the control mechanism for the wire-stitching machine;

Fig. 3 is a transverse sectional view taken on line 3—3 of Fig. 2 showing the oscillating mechanism for operating the work-feeding means;

Fig. 4 is a transverse sectional view taken on line 4—4 of Fig. 2 showing the tie-stitch operating means;

Fig. 5 is a transverse sectional view similar to Fig. 4 showing the pivoted key-raising arm as

rocked by the cam on the control shaft and latched in operative position;

Fig. 6 is a view similar to Fig. 5 illustrating the relationship of the parts at a later interval of the stitching operation and showing the lost motion between the parts of the oscillating mechanism for operating the work-feeding means;

Fig. 7 is a view similar to Fig. 5 showing the key-raising arm in its inoperative position and the key connecting the parts of the oscillating mechanism for movement as a unit;

Fig. 8 is a transverse sectional view showing the latch trip mechanism for releasing the key-raising arm of the tie-stitch mechanism;

Fig. 9 is a view similar to Fig. 8 showing the trigger of the latch trip mechanism operated by the lug on the trip-sleeve on the control shaft;

Fig. 10 is a transverse sectional view similar to Fig. 8 showing the trigger rocked with respect to the trip block by the trip-sleeve during the return movement of the control shaft;

Fig. 11 is a sectional view taken on line 11—11 of Fig. 7 showing the key for connecting the parts of the oscillating mechanism for movement as a unit and illustrating the eccentric contact element on the key-raising arm of the tie-stitch mechanism;

Fig. 12 is a plan view in reduced scale of several adjacent cartons showing the tie-stitch at the opposite ends of each row of stitches; and

Fig. 13 is a face view of the dial for adjusting the control means to adapt the machine to apply any predetermined number of stitches in a series.

The wire-stitching machine to which the present invention is applied is substantially identical with that illustrated and described in my United States Letters Patent No. 2,266,550, referred to above. Suffice it to state herein that the machine comprises a frame having a pedestal 2 with a horizontally extending arm 3 at its upper end, see Fig. 1. Below the arm 3 is a work-supporting table 4 mounted by means of brackets 6 on an I-beam 5 projecting laterally from the pedestal 2, the outer end of the I-beam being supported

by a post 9. Projecting laterally from the pedestal 2 at the side opposite from the table 4 is a platform or shelf 7 which is supported on the pedestal by means of a bracket 8.

A wire-stitching head 12 is mounted at the end of the horizontally extending arm 3 and is operated by a drive shaft 13 extending through the arm and projecting beyond the pedestal. The wire-stitching head 12 may be of any suitable construction and, as herein illustrated, is of the type shown and described in United States Let-

ters Patent to H. G. Allen, No. 1,760,031, issued May 27, 1930. In this type of machine, during the first half-revolution of the drive shaft 13 a length of wire is cut, bent into U-shape and driven into the work; while during the second half-revolution of the drive shaft 13 the parts of the stitching mechanism are returned to initial position and another length of wire is fed into the head. A fly-wheel 14 is mounted for rotation on the extended end of the drive shaft 13 and is continuously driven from an electric motor 15 through a suitable belt 16. A clutch 17 is provided adjacent the fly-wheel 14 for connecting the latter to the drive shaft 13. As described in detail in my prior patent referred to above the clutch 17 is operated automatically by a gate 18 positioned below the head 12 at the rear of a guide 19 and actuated by the work W.

The work in the form of carton blanks W, shown in Fig. 12, is fed intermittently in timed relation to the wire-stitching mechanism in the head 12 by means of spaced pairs of feed rollers 20 and 21, see Fig. 1. The upper feed rolls 20 are mounted on a shaft 23 journaled in suitable bearings depending from the arm 3 of the frame 2 driven from a shaft 24. The shaft 24 is journaled in suitable bearings on the platform 7 and connected to the shaft 23 by a shaft 25 having universal joints at its ends. The lower pair of feed rolls 21 are mounted at one side of a rockable frame 22 which is rocked to one position to engage the feed rolls with the work to advance the latter under the stitching head 12 and thereafter rocked to another position by a spring 26 to engage a pair of continuously-operating discharge rolls (not herein shown) with the work to discharge it from the machine. The lower feed rolls 21 are carried by a shaft 28 journaled in suitable bearings in the frame 22 and driven by a shaft 29 journaled in suitable bearings on the platform 7 and connected thereto by a shaft 30 having universal joints at its ends.

The shafts 24 and 29 carry intermeshing gears 31 and 32 and the lower shaft 29 is intermittently operated by a one-way clutch 33 enclosed in a housing 34 and actuated by a relatively movable crank-arm 35, see Fig. 1. The crank-arm 35 of the one-way clutch 33 is connected to an arm 36 of an oscillating mechanism 37 by a link 38, see Figs. 2 and 3. The oscillating mechanism 37 is in turn operated by a pitman 39 driven from an eccentric on the drive shaft 13. The arrangement of the one-way clutch 33 is such that during the first half-revolution of the drive shaft 13 to operate the wire-stitching mechanism in the head 12 to apply a stitch to the work the eccentric on the drive shaft actuates the pitman 39 and through the oscillating mechanism 37 moves the crank-arm 35 of the one-way clutch through an idle stroke with respect to the housing 34. During the second half-revolution of the drive shaft 13 while the wire-stitching mechanism in the head 12 is inoperative the oscillating mechanism 37 is operated by the pitman 39 to move the crank-arm 35 of the one-way clutch through a return stroke which in this direction of movement grips the housing 34 connected to the shaft 29 to rotate the latter through a predetermined arc. Thus, during the return stroke of the wire-stitching mechanism the spaced pairs of feed rolls 20, 21 are operated by the shafts 24, 29 connected to the shafts 25, 30 and shafts 23, 28 to advance the work a predetermined increment of movement.

The oscillating mechanism 37, see Figs. 2 and

3, comprises a hub-member 41 rockably mounted on a control shaft 45 and having flanges 42 and 43 at its opposite ends with radially-projecting ears between which the end of the pitman 39 is connected by a crank-pin 40. Rockably mounted on the hub-member 41 between the flanges 42 and 43 is a second hub-member 44 having the radially-projecting crank-arm 36. As illustrated in Figs. 7 and 11, a key 46 is positioned in a slot 47 in the periphery of the hub-member 44 of the oscillating mechanism 37, being pivotally mounted on a pin 48. The key 46 is rocked resiliently in a counterclockwise direction as viewed in Fig. 11 by means of a spring 49 to maintain its outer end 50 in a slot 51 in the periphery of the flange 43 of the hub-member 41. The end of the key 46 projects laterally beyond the side of the flange 43 of the hub-member 41 to overhang the latter for a purpose as will later appear. When the key 46 is seated in the slot 51 of the flange 43 of the hub-member 41 the two parts 41 and 44 of the oscillating mechanism 37 will rock as a unit. When the key 46 is rocked to the position illustrated in Figs. 5 and 6 the members 41 and 44 of the oscillating mechanism 37 may move relatively of each other to provide lost motion. A lug 52 on the flange 43 of the member 41 carries an adjustable set-screw 53 for engaging the side of the key 46 when the latter is raised to the position illustrated by dash-lines in Fig. 11 whereby to operate the work feeding means with lost motion. An abutment shoulder 54, see Fig. 6, is also provided on the flange 43 of the member 41 at the end of the slot 51 for engaging the opposite side of the key.

Referring to Figs. 1 and 2, the control shaft 45 is journaled in bearings in standards 56 and 57 mounted on the platform 7. Mounted fast on the control shaft 45 adjacent the side of the flange 42 of the oscillating member 41 is a ratchet-wheel 58, see Figs. 2 and 3. The control shaft 45 is intermittently rotated in timed relation to the operation of the work-feeding means by means of a pawl 59 pivoted to an ear 60 on the flange 42 of the oscillating member 41. A check-pawl 61 acts to hold the ratchet-wheel 58 from retrogressive movement during the return stroke of the oscillating member.

A gear 62 keyed to the control shaft 45 meshes with the teeth of a rack 63 slidable in a suitable guideway 64 in the frame of the bearing 56, see Figs. 2 and 3. Due to the arrangement of the teeth on the ratchet-wheel 58 the control shaft 45 is rotated during each forward stroke of the oscillating mechanism 37 to an extent sufficient to advance the rack 63 a distance of one tooth. The rack 63 is adapted to actuate stopping means (not herein shown) for disengaging the clutch 17 and the number of teeth that the rack 63 is advanced during a stitching operation determines the number of stitches S applied to the work W. The rack 63 is set for operation by means of an adjustable abutment 65 engageable by the rearward end of the rack, the abutment being carried at the end of a rod 66 adapted to be locked in any particular position of adjustment by a clamping member 55 embracing the rod and having a screw-threaded stem for receiving a clamping nut 70, see Figs. 2 and 3. It will be understood that the opposite or forward end of the rack 63 is adapted to engage and operate the stopping means to automatically arrest the operation of the stitching mechanism in the head 12 and engage the discharge rolls (not

herein shown) with the work. Upon arrestment of operation of the stitching mechanism a pawl-releasing lever 61 is actuated to cause it to engage the pawls 59 and 61 and release them from the teeth of the ratchet-wheel 58, see Fig. 2. A clock spring 68, see Fig. 2, having one end attached to the control shaft 45 and its opposite end connected to a stationary housing 69 acts to turn the shaft in clockwise direction as viewed in Fig. 3 to return the rack 63 to initial position when the pawls 59 and 61 are released from engagement with the ratchet-wheel 58. A dial 71 is also provided at the end of the control shaft 45 for manually rotating the latter to initially adjust its angular position, the dial being graduated to cooperate with a set-mark indicator on a bracket 72 to indicate the number of stitches to be applied during a stitching operation after any particular adjustment, see Fig. 13. As thus far described the construction of the stitching machine is identical with that illustrated and described in my prior patent referred to above.

In accordance with the present invention a novel form of tie-stitch operating mechanism is provided for automatically raising the key 46 at a predetermined interval of the stitching operation to cause the oscillating mechanism 31 to operate with lost motion. As the oscillating mechanism 31 drives the work-feeding rolls 20 and 21 the latter will advance the work with a reduced increment of movement between stitches when the key 46 is raised. Referring to Fig. 2, the tie-stitch operating mechanism is supported by the bracket 72 attached to the top of the bearing 51 by means of screws 73. The bracket 72 has an offset vertically extending block 74 with one face thereof positioned parallel to and spaced from the side of the flange 43 of the oscillating member 41.

A key-raising arm 75 is positioned between the face of the block 74 and the flange 43 of the oscillating member 41, see Figs. 2 and 5. The key-raising arm 75 is pivotally mounted intermediate its ends on the projecting end of a stud 76 carried by the block 74 of the bracket 72, the stud extending through the block and being held in position by a nut 77 screwed onto its threaded end, see Figs. 2 and 4. The key-raising arm 75 has an arcuate portion underlying the overhanging end of the key 46 and of a contour generally the same as that of the flange 43 of the oscillating member 41. At the opposite side of the pivot stud 76 from the arcuate portion the key-raising arm has an extension 78 provided with an inclined face 79 notched to provide a latch-shoulder 80. Mounted in a recess 84 in the arcuate portion of the key-raising arm 75 adjacent its end is an eccentric disk or contact element 81, see Figs. 5 and 11. The eccentric disk has a threaded stem 82 extending through the arm 75 and projecting therebeyond. A lock-nut 83 screwed onto the threaded stem 82 of the bearing element 81 is adapted to be set up against the side of the key-raising arm 75 to clamp the eccentric disk 81 in adjusted position on the arm, a spring 85 being provided between the head of the nut and the arm to frictionally resist turning of the nut. Thus, by loosening the nut 83 the eccentric disk 81 may be moved to its operative position illustrated in Figs. 5 and 11 or turned 180° to an inoperative position within the recess 84 in the key-raising arm 75.

The key-raising arm 75 is rocked on the pivot stud 76 from the position illustrated in Fig. 7 to that illustrated in Fig. 5 by a cam 86 on the

control shaft 45. The cam 86 is in the form of a sleeve attached to the control shaft 45 for rotation therewith by means of a pin 87 and having a lobe 88 engageable with the eccentric disk 81 on the arm. When the key-raising arm 75 is rocked on its pivot stud 76 to the position illustrated in Fig. 5 by the engagement of the cam lobe 88 with the eccentric disk 81 the arcuate portion of the arm will engage the overhanging end 10 of the key 46 to raise it out of engagement with the slot 51 in the flange 43 of the oscillating member 41, whereby the two parts 41 and 44 of the oscillating mechanism 31 operate with lost motion. Thus, the feed rolls 20 and 21 are rotated through a relatively short arc to advance the work less than the normal increment of movement between certain stitches to provide a tie-stitch. The operating cam 86 is preferably arranged on the control shaft 45 so that its lobe 88 is operative to actuate the key-raising arm 75 immediately after the next to that last stitch of a series has been applied to provide a tie-stitch at the end and at the beginning of successive rows of stitches, see Fig. 12.

25 An automatically operated latch 89 is provided for engaging the key-raising arm 75 to hold it in its operative position illustrated in Fig. 5. The latch 89 is in the form of a block having a latching nose 90 engageable with the latching shoulder 80 on the key-raising arm 75. The latch-block 89 is rigidly attached to a shaft 91 by means of a set-screw 92 and the shaft is journaled in the vertical block 74 and body-portion of the bracket 72, see Figs. 2 and 4. The latch-block 89 is also provided with a laterally extending arm 93 overlying the extension 78 of the key-raising arm 75 in spaced relation thereto and the ends of the spaced arms are connected by a helical spring 94. Thus, when the key-raising arm 75 is rocked from the position illustrated in Fig. 7 to that illustrated in Fig. 5 the spring 94, acting on the laterally extending arm 93 of the latch-block 89 automatically rocks the latter to engage its nose 90 with the latch-shoulder 80 to hold the key-raising arm in operative position.

40 A latch-trip mechanism is also provided for operating the latch-block 89 to release the key-raising arm 75 at a predetermined time during the operation of the stitching machine. The latch-trip mechanism comprises a trigger 98, see Figs. 2 and 4, carried by a trigger-block 99 on the shaft 91 and operated by a trip 100 on the control shaft 45. The trigger 98 is positioned in a recess 101 in the trigger-block 99 and pivotally mounted on a stud 102 projecting laterally from the trigger-block. The upper edge of the recess 101 in the trigger-block 99 is inclined as illustrated in Figs. 8, 9 and 10 to form a seat 103 for the trigger when the latter is in operative position as shown in Fig. 8. The trigger 98 is normally held in engagement with its seat 103 by means of a spring 104 coiled about the stud 102 with one end engaging the trigger and the opposite end engaging the cross-slot in the head of the stud. Thus, the spring 104 is operative to hold the trigger 98 in engagement with the seat 103 on the trigger-block 99, but is yieldable to permit the trigger to rock on the trigger-block as illustrated in Fig. 10. The end of the trigger 98 has a nose 105, the rearward face 106 of which is beveled or inclined for a purpose as will later appear.

45 The trip on the control shaft 45 is in the form of a split sleeve 100 to adapt it to be clamped in 50 adjusted position on the shaft. The periphery

of the sleeve 100 is reduced in diameter at one side to form an offset recessed face with which the nose 105 of the trigger 98 is adapted to engage, see Fig. 8. A lug 111 held in a slot in the peripheral rim of the sleeve 100 projects across the face 110. The lug 111 has a radially-extending face 112 for engagement with the nose 105 of the trigger 98 and an inclined rearward face 113. As illustrated in Figs. 8 and 9 the sleeve 100 has a screw 115 extending across its split portion to clamp it on the shaft 45. The trip-sleeve 100 may be loosened and rotated to any position of adjustment on the control shaft 45 to locate the lug 111 in any particular spaced relation to the nose 105 of the trigger 98 whereby to cause the latch-block 89 to be tripped at a predetermined time during the operation of the machine. Preferably, however, the trip-sleeve 100 is so positioned on the control shaft 45 as to operate the latch-block 89 after the second stitch of a series has been applied to the work W as indicated in Fig. 12. It will be understood that when the stitching mechanism is adjusted to apply any given number of stitches the operating cam 86 of the tie-stitch mechanism will actuate the key-raising arm 75 after the next to the last stitch has been applied as the cam is pinned to the control shaft 45 and moves in direct ratio to the rack 63 for operating the stopping means. The trip-sleeve 100, however, must be adjusted each time that the machine is set to apply a different number of staples in a series as the position of the lug 111 of the trip-sleeve 100 will have a particular angular relationship with respect to the trigger 98 at the beginning of a stitching operation depending upon the number of stitches to be driven in a series. A preferred form of the invention having been described in detail the mode of operation of the machine, and more particularly the tie-stitch mechanism, is as follows:

The machine is first adjusted to adapt it to apply a predetermined number of stitches S in a series and to advance the work W a predetermined increment of movement between the stitches in the manner described in detail in my prior patent referred to above. Suffice it to state herein that the rod 66 is released by turning the nut 70 to release the clamping member 55 and the control shaft 45 is turned by means of the graduated dial 71 to set it in a particular position corresponding to the number of stitches S to be applied. The adjustable abutment 65 is then brought into engagement with the rearward end of the rack 63 and clamped in adjusted position by tightening the nut 70. The distance that the rack 63 is moved rearwardly away from the stopping means (not herein shown but illustrated in my copending application) to its initial position determines the number of stitches to be applied during a stitching operation and the trip-sleeve 100 is turned to an adjusted position on the control shaft 45 to cause it to actuate the latch-trip trigger 98 after the second stitch of a series is applied.

The machine is then ready for a stitching operation which is initiated by inserting a carton W, shown in Fig. 12. When the carton W is inserted into the machine with its flaps on the top and bottom of the flap-guide 19 the end of the carton engages and actuates the gauge 18 which through suitable mechanism, engages the clutch 17 to couple the fly-wheel 14 to the drive shaft 13. During the first half-revolution of the drive shaft 13 a staple or stitch S is applied to the work W. Simultaneously with the

application of a stitch S during the first half-revolution of the drive shaft 13 the pitman 39 is operated from the position shown in Fig. 3 to that shown in Fig. 5. For convenience of description it may be considered that at the beginning of the stitching operation the tie-stitch cam 86 is in the position indicated by dash lines in Fig. 5 and as the tie-stitch mechanism has not been set for the first carton W the key-raising arm 75 is in the position indicated in Fig. 7. That is, the key 46 is seated in the slot 51 of the flange 43 of the oscillating member 41 whereby the two parts 41 and 44 of the oscillating mechanism 37 oscillate as a unit to operate the crank-arm 35 of the one-way clutch 33 through a full stroke. Due to the arrangement of the one-way clutch 33 the crank-arm 35 moves relatively of the housing 34 during the first half-revolution of the drive shaft 13. During the second half-revolution of the drive shaft 13 the crank-arm 35 rocks the housing 34 and shaft 29 connected thereto and through the gears 31 and 32, shaft 24, shafts 25 and 30 and shafts 23 and 28, operates the spaced pairs of feed rolls 20 and 21 through an arc to advance the work a predetermined increment of movement. It will be understood that when the work W is inserted into the machine the initial operation thereof rocks the feed rolls 21 toward the feed rolls 20 to grip the carton W therebetween. The machine continues to operate in the manner explained to apply a stitch during the first half-revolution of the drive shaft 13 and to intermittently advance the work W predetermined increments of movement between stitches during the second half-revolution of the drive shaft 13.

During each reciprocation of the pitman 39 the pawl 59 on the flange 42 of the oscillating mechanism 37 engages the teeth of the ratchet-wheel 58 on the control shaft 45 to turn the shaft through a predetermined arc, the control shaft being held against rearward movement between strokes of the pitman 39 by the check-pawl 61 engaging the teeth on the ratchet-wheel. The rotation of the control shaft 45 during each stroke of the pitman 39 is such as to advance the rack 63 a distance of one tooth toward the stopping means. Also, due to the rotation of the control shaft 45, the cam 86 is rotated intermittently from the position indicated by dash lines to the position illustrated by full lines in Fig. 5. The cam 86 is so positioned on the control shaft 45 that the rotation of the latter as the next to the last stitch of a series is applied will engage the lobe 88 of the cam with the eccentric disk 81 at the outer end of the key-raising arm 75 and rock the arm on its pivot-stud 16. Rocking movement of the arm 75 causes its outer arcuate edge to engage the overhanging end of the key 46 to raise it out of engagement with the slot 51 in the flange 43 of the oscillating member 41. During the first half-revolution of the drive shaft 13 to operate the stitching mechanism in the head 12 to apply the next to the last stitch of a series the two parts 41 and 44 of the oscillating mechanism 37 operate the crank-arm 35 of the one-way clutch 33 in the usual manner, but during the second half-revolution of the drive shaft 13 the member 41 moves relatively of the member 44 with lost motion until the adjustable abutment 53 on the member 41 engages the side of the key 46 to operate the crank-arm 35 through a considerably shorter arc, see Figs. 5 and 6. Thus, the work feed rolls 20 and 21 are moved through a re-

duced increment of movement between the next to the last stitch and last stitch of a series whereby the last two stitches are arranged closely adjacent each other to provide a tie-stitch at the end of the row of stitches.

When the key-raising arm 75 is rocked on its pivot 76 from the position illustrated in Fig. 7 to that illustrated in Fig. 5 the tension of the spring 94 acting on the arm 93 of the latch-block 89 rocks the latter to engage its nose 90 with the latch shoulder 80 on the key-raising arm. The key-raising arm 75 is thus latched in its operative position to cause the work-feeding means to continue to advance the work with a reduced increment of movement between stitches. Simultaneously with the application of the last stitch of a series the rack 63 is advanced to engage and operate the stopping mechanism which actuates the pawl-releasing lever 67 to disengage the pawls 59 and 61 from the teeth of the ratchet-wheel 58. The stopping means actuates the clutch 17 to release the fly-wheel 14 from driving engagement with the drive shaft 13 and the spring 68, see Fig. 2, rotates the control shaft 45 and, through the pinion gear 62, moves the rack 63 rearwardly until its end engages the abutment 65. Simultaneously with the return movement of the rack 63 the cam 86 is returned to its initial position indicated by dash lines in Fig. 5. It will be understood that upon operation of the stopping means the cradle or frame 22 carrying the feed rolls 21 is rocked to the position illustrated in Fig. 1 to engage the discharge rolls (not herein shown) with the work and thereby separate the pairs of feed rolls 20 and 21.

Upon insertion of the next carton W into the machine in the manner indicated in Fig. 12, operation of the machine is again initiated to drive the first stitch during the first half-revolution of the drive shaft 13 and advance the work during the second half-revolution of the drive shaft. As the key-raising arm 75 is latched in its operative position to hold the key raised the members 41 and 44 of the oscillating mechanism 37 move with lost motion to advance the work W a reduced increment of movement so that the second stitch S of the series is applied closely adjacent the first stitch to provide a tie-stitch at the beginning of a row or series of stitches. After the application of the second stitch the trip-sleeve 100 will have moved from the position illustrated in Fig. 8 to that illustrated in Fig. 9 to engage the radial face 112 of the lug 111 with the nose 105 of the trigger 98 to rock the trigger-block 99 and shaft 91 carrying the latch-block 89. Upon rocking movement of the latch-block 89 the spring 94 acting on the extension 78 of the key-raising arm 75 rocks the latter to its inoperative position shown in Fig. 7. Upon release of the key 46 by the arm 75 the key is rocked on its pivot 48 by the spring 49 to engage its end in the slot 51 in the flange 43 of the oscillating member 41. The parts 41 and 44 of the oscillating mechanism 37 thereafter oscillate as a unit to operate the feed rolls 20 and 21 through a maximum arc to advance the work W a normal increment of movement between stitches S whereby to apply a row of stitches in the manner shown in Fig. 12. The stitching mechanism in the head 12 and the work-feed rolls 20 and 21 then continue to operate in the manner explained until the cam 86 has been moved to engage the eccentric disk 81 on the key-raising arm 75 whereby to

again initiate the operation of the tie-stitch means. It will be understood that at the beginning of the stitching of the first carton the key-raising arm 78 may be rocked manually to 5 latch it in the position illustrated in Fig. 5 so that the machine will apply a tie-stitch at the beginning of the row of stitches as well as at the end of the row.

During the return movement of the control 10 shaft 45 after a stitching operation the inclined face 113 of the lug 111 on the trip-sleeve 100 will engage the inclined face 106 on the trigger 98 to rock the trigger against the action of the spring 104 whereby to permit the lug to pass 15 by the trigger without operating the latch-block 89 between stitching operations, see Fig. 10. It will be understood that the trip-sleeve 100 is adjustable on the control shaft 45 to adapt it to operate the trigger 98 at any particular time 20 during a stitching operation and the form of the cam 86 and trip-sleeve 100 may be varied to apply a tie-stitch intermediate a row as well as at the beginning and end of a row of stitches. Furthermore, it will be understood that if it is 25 desired to operate the machine without a tie-stitch the nut 83 may be loosened on the stem 82 of the eccentric disk 81 and the latter turned into the recess 84 in the key-raising arm 75 whereby the cam 86 will not engage the disk 30 to rock the key-raising arm on its pivot.

It will be observed from the foregoing specification that the present invention provides a novel form of tie-stitch operating means which is of simple and compact construction and actuated directly from the control shaft. It will be observed further that the present invention provides a tie-stitch mechanism which may be operated during the next to the last stitch of a series and latched in operative position during 35 the completion of a stitching operation and at the beginning of a subsequent stitching operation whereby one setting of the tie-stitch means effects a tie-stitch at the end of one series of stitches and the beginning of another series.

45 While a preferred form of the invention is herein illustrated and described, it will be understood that modifications may be made in the form and arrangement of the parts thereof without departing from the spirit or scope of the invention. Therefore, without limiting myself in 50 this respect, I claim:

1. In a machine of the type indicated, the combination of wire-stitching means, work-feeding means, driving means for operating the 55 wire-stitching means and work-feeding means in timed relationship, tie-stitch means for controlling the operation of the feeding means to reduce the increment of movement of the work by the feeding means between certain stitches, an angularly-movable cam actuated in one direction by the driving means for controlling the operation of the tie-stitch means, and means for moving the cam in the opposite direction to return it to initial position after a stitching operation.

2. In a machine of the type indicated, the combination of wire-stitching means, work-feeding means, driving means for operating the wire-stitching means and work-feeding means in timed relationship, tie-stitch means for controlling the operation of the feeding means to reduce the increment of movement of the work by the feeding means between certain stitches, an angularly-movable cam driven by the driving means for 70 controlling the operation of the tie-stitch means,

and means for initially adjusting the relative position of the cam with respect to the tie-stitch means to adapt the tie-stitch means to be operated after any number of stitches have been applied to the work.

3. In a machine of the type indicated, the combination of wire-stitching means having a predetermined period of operation to apply a series of stitches, work-feeding means, driving means for operating the wire-stitching means and work-feeding means in timed relationship, tie-stitch means for controlling the operation of the feeding means to reduce the increment of movement of the work by the feeding means between the first and last two stitches of the series applied to the work, a cam actuated in one direction by the driving means for controlling the operation of the tie-stitch means, and means for moving the cam in the opposite direction to return it to initial position after a stitching operation.

4. In a machine of the type indicated, the combination of a wire-stitching means, work-feeding means, driving means for operating the wire-stitching means and work-feeding means in timed relationship, tie-stitch means for controlling the operation of the feeding means to reduce the increment of movement of the work by the feeding means between certain stitches, and means operated by the driving means for controlling the period of operation of the wire-stitching means and the time of operation of the tie-stitch means, said last-named means comprising a cam movable in one direction for operating the tie-stitch means, and means for moving the cam in the opposite direction to return it to its initial position after a stitching operation.

5. In a machine of the type indicated, the combination of wire-stitching means having a predetermined period of operation to apply a series of stitches, work-feeding means, driving means for operating the wire-stitching means and work-feeding means in timed relationship, tie-stitch means for controlling the operation of the feeding means to reduce the increment of movement of the work by the feeding means between certain stitches, a control shaft driven from the driving means, a cam on the control shaft for operating the tie-stitch means, and means for rotating the control shaft back to initial position after a stitching operation.

6. In a machine of the type indicated, the combination of wire-stitching means having a predetermined period of operation to apply a series of stitches, work-feeding means, driving means for operating the wire-stitching means and work-feeding means in timed relationship, tie-stitch means for controlling the operation of the feeding means to reduce the increment of movement of the work by the feeding means between certain stitches, a control shaft, a cam thereon for operating the tie-stitch means, means operated by the driving means for intermittently rotating the control shaft in timed relation therewith, and means for rotating the control shaft back to initial position after a stitching operation.

7. In a machine of the type indicated, the combination of wire-stitching means, work-feeding means, driving means for operating the wire-stitching means and work-feeding means in timed relationship, tie-stitch means for controlling the operation of the feeding means to reduce the increment of movement of the work

by the feeding means between certain stitches, a control shaft operated by the driving means, a cam fixed to the control shaft for operating the tie-stitch means, and manually-operable means for initially adjusting the angular position of the control shaft to operate the tie-stitch means after any predetermined number of stitches.

8. In a machine of the type indicated, the combination of wire-stitching means, work-feeding means, driving means for operating the wire-stitching means and work-feeding means in timed relationship, tie-stitch means for controlling the operation of the feeding means to reduce the increment of movement of the work by the feeding means between certain stitches, means for initiating operation of the wire-stitching means, means for stopping the wire-stitching means, a control shaft operated by the driving means, means operated by the control shaft for initiating operation of the tie-stitch means and the stopping means for the wire-stitching means, and manually-operable means for initially adjusting the angular position of the control shaft to vary the period of operation of the wire-stitching means and the time of operation of the tie-stitch means.

9. In a machine of the type indicated, the combination of wire-stitching means, work-feeding means, driving means for operating the wire-stitching means and work-feeding means in timed relationship, tie-stitch means for controlling the operation of the feeding means to reduce the increment of movement of the work by the feeding means between certain stitches, a control shaft operated by the driving means, a cam on the control shaft for operating the tie-stitch means, means operated by the control shaft for stopping the wire-stitching means, and manually-operable means for initially adjusting the angular position of the control shaft to vary the period of operation of the wire-stitching means and the time of operation of the tie-stitch means.

10. In a machine of the type indicated, the combination of wire-stitching means, work-feeding means, driving means for operating the wire-stitching means and work-feeding means in timed relationship, tie-stitch means for controlling the operation of the feeding means to decrease the increment of movement of the work by the feeding means between certain stitches, means for initiating the operation of the tie-stitch means, means for latching the tie-stitch means in operative position, and means for releasing the latching means.

11. In a machine of the type indicated, the combination of wire-stitching means, work-feeding means, driving means for operating the wire-stitching means and work-feeding means in timed relationship, tie-stitch means for controlling the operation of the feeding means to reduce the increment of movement of the work by the feeding means between certain stitches, a cam operated from the driving means for initiating operation of the tie-stitch means, means for latching the tie-stitch means in operative position, and means operated from the driving means for releasing the latching means.

12. In a machine of the type indicated, the combination of wire-stitching means, work-feeding means, driving means for operating the wire-stitching means and work-feeding means in timed relationship, a control shaft driven from the driving means, tie-stitch means for control-

ling the operation of the work-feeding means to reduce the increment of movement of the work by the feeding means between certain stitches, a cam on the control shaft for initiating operation of the tie-stitch means, means for latching the tie-stitch means in operative position, and means operated by the rotation of the control shaft for releasing the latching means.

13. In a machine of the type indicated, the combination of wire-stitching means, work-feeding means, means for driving the wire-stitching means and work-feeding means in timed relationship to apply a series of spaced stitches to the work, tie-stitch means for controlling the operation of the feeding means to reduce the increment of movement of the work by the feeding means during the first and last two stitches of a series, means operated by the driving means for operating the tie-stitch means during application of the next to the last stitch of a series, means for automatically latching the tie-stitch means in operative position, and means operated from the driving means for actuating the latching means to release the tie-stitch means during the application of the second stitch of the next series.

14. In a machine of the type indicated, the combination of wire-stitching means, work-feeding means, means for driving the wire-stitching means and work-feeding means in timed relationship to apply a series of spaced stitches to the work, tie-stitch means for controlling the operation of the feeding means to reduce the increment of movement of the work by the feeding means between the first and last two stitches of a series, a control shaft driven from the driving means, a cam on the shaft for operating the tie-stitch means during the application of the next to the last stitch, means for automatically latching the tie-stitch means in operative position, and means on the control shaft for actuating the latching means to release the tie-stitch means during the application of the second stitch of the next series.

15. In a machine of the type indicated, the combination of wire-stitching means, work-feeding means, means for driving the wire-stitching means, a control shaft driven from the driving means, means for operating the work-feeding means from the driving means in timed relation to the wire-stitching means comprising a pair of relatively movable members, means connecting the members for movement as a unit or with lost motion, a cam fixed to the control shaft for operating the connecting means, and manually-operable means for initially adjusting the angular position of the control shaft to operate the tie-stitch means after any predetermined number of stitches.

16. In a machine of the type indicated, the combination of wire-stitching means, work-feeding means, means for driving the wire-stitching means, a control shaft driven from the driving means, a pair of members mounted to oscillate on the control shaft and connected to operate the work-feeding means, said members having interengaging parts for oscillating one from the other with lost motion, a key for connecting the members for oscillation as a unit, and a cam on the control shaft for operating the key to disconnect the oscillating members during certain periods of operation of the wire-stitching means.

17. In a machine of the type indicated, the combination of wire-stitching means, work-feeding

means, means for driving the wire-stitching means, a control shaft driven from the driving means, means for operating the work-feeding means from the driving means in timed relation

5 to the wire-stitching means comprising a pair of members mounted to oscillate on the control shaft, interengaging means on the members for rocking one from the other with lost motion, a key for connecting the members for oscillation as a unit, a member for disengaging the key to release the oscillating members, and a cam on the control shaft for operating the key-disengaging member at a predetermined time during a stitching operation.

15 18. In a machine of the type indicated, the combination of wire-stitching means, work-feeding means, means for driving the wire-stitching means, a control shaft driven from the driving means, means for operating the work-feeding

20 means from the driving means in timed relation to the wire-stitching means comprising a pair of members mounted to oscillate on the control shaft, interengaging means on the members for rocking one from the other with lost motion, a key for connecting the members for oscillation as a unit, a member for disengaging the key to release the oscillating members, a cam on the control shaft, and manually-operable means for initially adjusting the control shaft to adapt

25 the cam to operate the key-disengaging member after any predetermined number of stitches have been applied to the work.

19. A work-feeding device for wire-stitching machines comprising a pair of members having

35 cooperating means engageable to drive one member from the other with lost motion, means for connecting the members for movement together as a unit, a rockable member for actuating the last-named means to disconnect the members, a cam for actuating the rockable member at a predetermined time during the operation of the device, a latch for locking the rockable member in operative position, and means for operating the latch to release the rockable member.

45 20. A work-feeding device for wire-stitching machines comprising a control shaft, a pair of members mounted to oscillate on the control shaft, said members having cooperating means engageable to drive one member from the other

50 with lost motion, a key for connecting the members to oscillate as a unit, a member for disengaging the key to release the members, a cam on the control shaft for operating the key-disengaging member at a predetermined time during the operation of the device, a latch for locking the key-disengaging member, a trip-block connected to the latch, and a trip-member on the control shaft for operating the trip-block whereby to actuate the latch to release the key-disengaging member.

60 21. A work-feeding device for wire-stitching machines comprising a control shaft, a pair of members mounted to oscillate on the control shaft, said members having cooperating means engageable to drive one member from the other with lost motion, a key for connecting the members to oscillate as a unit, a pivoted member for

65 raising the key to release the members, a cam on the control shaft for rocking the pivoted member at a predetermined time, a rockable latch for locking the pivoted member in operative position, a spring connecting the key-raising member and latch, a trip-block connected to the latch, a trigger pivotally mounted on the trip-block, and means on the control shaft engageable

with the trigger on the trip-block for operating the latch to release the key-raising member, said trigger operating the trip-block in one direction of movement and movable with respect to the trip-block in the opposite direction of movement.

22. A work-feeding device for wire-stitching machines comprising a pair of members having cooperating means engageable to drive one member from the other member with lost motion, means for connecting the members for move-

ment together, as a unit, a pivoted member for actuating the last-named means to disconnect the members, an eccentric element on the last-named member, and a cam for engaging the eccentric element at a predetermined time for operating the pivoted member to disconnect the members, said eccentric element being rotatable on the member on which it is mounted whereby it may be moved out of position to be engaged by the cam.

GEORGE H. HARRED.
